INVENTOR
BY Victor J. Evans

WITNESS:

ATTORNEY

UNITED STATES PATENT OFFICE.

JOHN O. HOCHER, OF JANEVILLE, WISCONSIN.

FURNACE.

Application filed February 20, 1925. Serial No. 10,623.

This invention relates to new and useful improvements in heating systems and more particularly to a combination of hot water and hot air heating system. The main object of my invention is the provision of a heating system combining both hot air and hot water whereby to utilize the maximum amount of heat for minimum amount of fuel used.

Another object of my invention is the provision of a heating system wherein the usual conveyors for the hot water and hot air are so arranged relative to the heating plant as to utilize a maximum amount of heat from the fuel consumed and convey the hot air and hot water to the interior of the building to be heated.

Another object of my invention is the provision of a heating system wherein the smoke and heat from the burning fuel is utilized to the fullest extent before being passed out through the usual smoke stack so as to provide for thoroughly heating of the hot air conduits and hot water conduits.

With the above and other objects in view, my invention consists in the novel features of construction and the combination and arrangement of parts to be hereinafter more fully described, pointed out in the claims and shown in the accompanying drawings, in which:

Fig. 1 is a longitudinal sectional view of a device constructed in accordance with my invention, parts thereof being shown in elevation,

Fig. 2 is a front elevation,

Fig. 3 is a transverse section on the line 3—3 of Figure 1, and

Fig. 4 is a detail section on the line 4—4 of Figure 1.

Referring now more particularly to the drawings, the numeral 1 indicates the furnace in which the fuel is burned and adapted to be inserted in the furnace through the fire door 2. The furnace is provided with an ash door 3 whereby the ashes may be readily removed from the furnace. The interior construction of the furnace such as the grate and the like are immaterial relative to my improved system, but that type of furnace having a water jacket 4 is essential, said water jacket extending upwardly and over the top of the furnace, as shown at 5 and provided

with a head 6. The smoke conduit 7 is connected to the head 6 and extends upwardly at an angle in the air chamber 8 into a head 9 which receives the smoke and heat and then diverts the same in an opposite direction on an inclined angle into the conduit 10, the upper end of which has communication with a smoke stack 11. From this it will be apparent that the heat and smoke from the burning fuel in the furnace 1 is caused to travel a considerable distance before entering the smoke stack 11, and thus the conduits 7 and 10 will be thoroughly heated to throw off enough heat to heat the air in the chamber 8. This chamber 8 is formed of a large casing 12 supported upon the top of the furnace.

The head 9 of the smoke conduits 7 and 10 is supported by means of a pillar 13 which extends through an opening in the bottom of the casing 12.

The hot water from the jackets 4 and 5 is diverted into the pipes 14 arranged in the inclined smoke and head conduit 7 with the lower ends communicating with the water jacket at 15. The upper ends of these pipes 14 communicate with the reservoir 16 arranged in the head 9, this reservoir receiving the water from the pipes 14 and diverting it into the upwardly inclined pipes 17 which extend in divergent relation relative to the pipes 14 in the smoke and heat conduit 10 and communicate at their upper ends with a head or reservoir 18 arranged in the upper end of the conduit 10 at a point adjacent the entrance to the smoke stack 11. From this arrangement it will be apparent that the water in the pipes 14 and 17 will be thoroughly heated before passing into the head or reservoir 18. The reservoir 18 is connected with the radiators or other suitable heating elements in the building by means of a supply pipe 19 while the chamber 8 may be connected in any suitable manner to the hot air registers through the medium of a conduit 20 which opens outwardly from the top of the hot air chamber 8 at a point adjacent the smoke stack 11.

It will be apparent from the foregoing that by arranging the water pipes 14 in the smoke and heat conduits 7 and 10 the water therein will be subjected to the full amount of the heat from the fire in the furnace 1 and cause the water to flow around

through the pipes in the conduits which provide for thorough heating of the water before the same passes out through the supply pipe 19.

5 It will also be apparent that by causing the heat and smoke to travel through the divergent conduits 7 and 10 they will be heated and radiate considerable heat therefrom into the air chamber 8 and the heated air will 10 then pass out through the conduit 20.

To permit the circulation of air through the air chamber 8 to pass in heated condition through the conduit 20 it is necessary to provide a cold air inlet. This cold 15 air inlet is indicated at 8' in Fig. 1 of the drawings and preferably, but not necessarily, passage through this inlet is controlled by a shutter plate 9' of a well known construction.

20 In order to create the proper circulation of the smoke and heat as it rises from the furnace 1, an air opening 21 is formed in the front of the furnace near the top thereof and in alignment with the lower side of the conduit 7, thus creating proper drift toward the smoke stack 11.

In order to provide means whereby to clean the conduit 10 a similar opening 22 is provided normally closed by means of a 30 swinging door 23.

Attention is also directed to the arrangement of the reservoir 16 in the head 9, as it will be apparent that this reservoir receives the heat direct from the furnace 1 and that 35 the water coming into the reservoir from the pipes 14 will be maintained in a highly heated condition before passing upwardly through the pipes 17 and will be retained in a highly heated condition upon reaching the reservoir 18 prior to being passed out through 40 the supply pipe 19. Any suitable means may be provided for conveying the supply of water to the water jackets 4 and 5.

From the above it will be apparent that I 45 have provided a combination of a hot air and hot water heater wherein the full heating capacity of a furnace is utilized and a building may be provided with both a hot air and a hot water heating system in accordance with 50 my idea.

It will be noted that as the water has passed through the usual radiators it is returned to the water jacket 4 in any desired manner and directed through the openings 55 4^a in the bottom of the furnace as shown in Figure 2 so as to provide for continuous circulation of the water.

While I have shown and described the 60 preferred form of my invention, it will be obvious that various changes in the details of construction and in the proportions may be resorted to for successfully carrying my invention into practice without sacrificing any of the novel features or departing from 65 the scope of the appended claims.

Having thus described my invention, what I claim is:

1. In combination a furnace including a water jacket, a casing above the furnace forming an air chamber, conduits, having communication with the furnace and extending in alternate directions through the air chamber, an outlet communicating with the conduits at the end opposite the furnace, a plurality of pipes having communication with the water jacket and extending in alternate directions through the air chamber within the conduits and a supply pipe connected with the end of the pipes opposite the water jacket. 75

2. In combination a furnace including a water jacket, a casing above the furnace forming an air chamber, conduits extending in opposite directions through the casing and having communication at one end with the furnace, and water pipes having communication with the water jacket and extending through said conduits. 80

3. In combination a furnace including a water jacket, a casing forming an air chamber above the furnace, conduits extending in alternate directions through the air chamber and having communication with the furnace, a smoke stack communicating with the conduits, an outlet conduit having communication with the air chamber and water pipes having communication with the water jacket and extending through alternate conduits. 95

4. In combination a furnace including a water jacket, conduits extending in alternate directions and having communication with the furnace, an outlet conduit communicating with the conduits at the end opposite the communication with the furnace, water pipes communicating at one end with the water jacket and extending in alternate directions through the conduits and a supply pipe connected with the water pipes at the end opposite that having communication with the water jacket. 100

5. In combination a furnace including a water jacket, an inclined conduit having communication with the furnace at one end, a head at the other end forming a chamber, a second conduit arranged in divergent relation with the first conduit communicating at one end with said chamber, an outlet conduit having communication with the other end and water pipes having communication with the water jacket and heads and extending through said conduits. 115

6. In combination a furnace including a water jacket, a conduit having communication with the furnace at one end, a head forming a chamber at the other end, a second conduit arranged in divergent relation with the first conduit and having one end communicating with the chamber, an outlet conduit at the other end, water pipes having one 125 130

- end communicating with the water jacket and extending through the first conduit, a reservoir arranged in the chamber and connected with the ends of the pipes opposite 5 the ends connected to the water jacket, a second set of pipes in the second conduit communicating with one end of the reservoir, a second reservoir at the other end of the second set of pipes and having communication 10 therewith and a supply pipe connected to the second reservoir for receiving water from the second reservoir.
7. In combination a furnace including a water jacket, a casing forming a hot air 15 chamber arranged above the furnace, a con-
- duit communicating at one end with the furnace, a head forming a chamber at the one end of the conduit, a second conduit arranged in divergent relation with the first conduit and communicating with the chamber, an outlet conduit communicating with the end of the second conduit opposite the end connected to the chamber and water pipes communicating at one end with the water jacket and extending through said 20 conduits and a second set of pipes having communication with the other water pipes. 25

In testimony whereof I affix my signature.

JOHN O. HOCHER.
